UNITED STATES PATENT OFFICE.

EDWARD B. MERRIMAN, OF BOSTON, MASSACHUSETTS.

BRIDLE ATTACHMENT.

No. 820,658.

Specification of Letters Patent.

Patented May 15, 1906.

Application filed March 27, 1905. Serial No. 252,130.

To all whom it may concern.

Be it known that I, EDWARD B. MERRIMAN, a citizen of the United States, and a resident of Boston, in the county of Suffolk and State 5 of Massachusetts, have invented certain new and useful Improvements in Bridle Attachments, of which the following is a specification.

My invention relates primarily to the devices commonly called "bridles" or "spans" which are used on yachts for the purpose of detachably connecting a block or the like to a piece of rope secured at both ends to the boom or gaff of a sail and forming the bridle proper. Such devices are in common use for connecting the peak-halyard block to the gaff, for example, the connection being detachable in order that when the sail is furled the sail-cover may be applied without being interfered with by the presence of the peak-halyard.

The bridle attachments usually employed heretofore have been found to be unsatisfactory for one reason or another, being difficult to open and close in cold weather or in the dark, as well as liable to open accidentally, and my invention is accordingly intended to provide a strong and durable device of this character which may be quickly and easily applied to or detached from a bridle or the like at any time and under any conditions of weather and which when attached will have its parts so held in the closed position that there will be no danger of accidental disengagement of the device.

In the accompanying drawings, Figure 1 is a side elevation of a yacht-block of a well-known type, combined with my bridle attachment in its preferred form. Fig. 2 is an 40 edge view, partly in section, of the parts shown in Fig. 1. Fig. 3 is a view similar to Fig. 1, showing my attachment as applied to an eye instead of a block.

Referring to Figs. 1 and 2 of the drawings, 45 Fig. 2 indicates a metallic shell containing the usual sheave 3 and provided at its upper end with a lug 4. This lug carries a two-part U-shaped member, one of the parts of which is herein represented as a saddle or hook-shaped member 5, the upper portion of which has the usual form and contour to receive the bridle or rope. One side 5^a of this saddle member is made longer than the other and is mounted at its lower end on a pivot 6, which 55 preferably passes through the lug 4 and pro-

jects from the opposite side of the same, as shown at 7, for a purpose which will herein-after appear.

8 represents a cover which is hinged to one side of the member 5, as at 9, in such manner 60 as to be capable of swinging outward into the position shown in dotted lines in Fig. 2, thus opening a side entrance to the space beneath the saddle, which receives the rope or bridle. When the cover 8 is swung downward into 65 the position shown in full lines in Fig. 2, it abuts against the lug 4 and closes said entrance, and suitable means are employed for holding the cover in this closed or normal position. Said means are preferably provided 70 by forming a curved lip 10 on the lower edge of the cover concentric with the pivot 6 and a shoulder 11 at the upper end of the block 2, behind which shoulder said lip is adapted to pass. The cover 8 is perforated to receive 75 snugly the projecting end of the pivot 6 or any equivalent projection which may be formed on the lug 4, and the lip 10 terminates at such a point that when the shell 2 and the saddle member and cover are sufficiently 80 turned with relation to each other on the pivot 6 as a center, the shoulder 11 will be carried beyond one end of the lip 10, whereupon the cover 8 may be swung outward into 85 position to permit the insertion or removal of the rope or bridle proper. When the cover is in the closed position, however, and the block and the saddle member are in any other relative position than the one above referred to, the cover will be prevented from opening by 90 the engagement of the lip 10 with the shoulder 11, and inasmuch as the extreme position which it is necessary for the parts to assume in order that the cover may be released is one which is exceedingly unlikely to be assumed 95 in use and cannot be assumed when the parts are under tension the accidental release of the bridle will be practically impossible.

In Fig. 3 the saddle member 5 and its cover 8 are shown as constructed in the same manner as is illustrated in Figs. 1 and 2, but in this figure the block 2 is replaced by an ordinary eye 12, the upper end of which is provided with a lug and lip-engaging shoulder corresponding in all respects to the lug and 100 shoulder already described. It will be understood that a similar lug and lip-engaging shoulder may be formed as well on the strap of a wooden block or upon any other part to 105 which it is desired to apply my attachment. 110

I prefer to so proportion the cover and its lip that the latter may be released from the retaining-shoulder in either one of the two extreme positions which the saddle member 5 may assume with respect to the block or other part to which it is attached, one of these positions being shown in dotted lines in Fig. 3.

It will be observed as one result of the construction above described that the strain on 10 the saddle member is supported in part by the cover and applied to both ends of the pivot-pin 6 by reason of the projection of the latter through the perforation in the cover, so that there is no tendency for the saddle 15 member to cramp or bind on its pivot in use. It will also be seen that the parts are so guided by the flat sides of the lug that loose play between them is prevented, such play being a disadvantageous feature of a common 20 form of bridle attachment heretofore used. The saddle member may be so applied to the lug 4, if desired, that it will swing in a plane at right angles to the plane of the sheave instead of in the latter plane, which 25 may be advantageous in some cases. However its parts may be arranged, my device can always be easily and quickly operated and is not likely to break or get out of order.

I do not consider my invention to be limited to the precise means herein described for locking the cover in its closed position or to the specific construction and arrangement of the various parts of my device, and it will be evident that my invention may be embodied 30 in other devices than bridle attachments, such as various forms of hooks and the like, in case it is desired to prevent the accidental removal of such a device from the part with which it is engaged.

35 40 I claim as my invention—

1. In a device of the character described, the combination with an attaching-lug of a saddle or hook shaped member having its longer side pivoted thereto, the opposite side 45 of said lug being provided with a projection, a cover hinged to said saddle member and perforated to receive said projection, and means for normally holding said cover in its closed position.

50 55 2. In a device of the character described, the combination with an attaching-lug of a U-shaped member comprising two parts hinged together and adapted to embrace said lug at their free ends, one of said parts being secured to the lug at one side of the same, and means for normally holding the other part against the opposite side of said lug.

60 65 3. In a device of the character described, the combination with an attaching-lug of a U-shaped member pivoted thereto and comprising two parts hinged together, one of said parts being movable toward the lug, and interlocking means for normally holding the latter part against the lug.

4. In a device of the character described,

the combination with an attaching-lug of a saddle or hook shaped member pivoted thereto and having a side-opening, and interlocking means for closing said opening when said parts are in normal relative position.

5. In a device of the character described, the combination with an attaching-lug having a locking-shoulder, of a saddle or hook shaped member pivoted to said lug, and a cover hinged to said member and provided 70 with a lip adapted to pass behind said shoulder when the parts are moved into normal position.

6. In a device of the character described, the combination with an attaching-lug of a saddle or hook shaped member pivoted thereto, the opposite side of said lug being provided with a projection, and a cover hinged to said saddle member and perforated to receive said projection, said cover and lug 80 being provided with means adapted to interlock 85 when the parts are in normal relative position.

7. In a device of the character described, the combination with an attaching-lug having a locking-shoulder, of a saddle or hook shaped member connected with said lug by a pivot-pin having a projecting free end, and a cover hinged to said saddle member and perforated to receive the free end of said pin, 90 said cover being provided with a curved lip 95 adapted to engage said shoulder, and to pass from under the same in an abnormal relative position of said parts.

8. In a device of the character described, the combination with an attaching-lug having its opposite sides flat and parallel, of a saddle or hook shaped member pivoted to one side of said lug in contact therewith, said member having a side opening, a cover for 100 said opening and means for locking said cover in its closed position.

9. In a device of the character described, the combination with an attaching-lug having its opposite sides flat and parallel, of a U-shaped member comprising two parts hinged together and adapted to embrace the flat sides of said lug at their ends, one of said parts being pivoted to one side of the lug, and means for normally holding the other part 115 against the opposite side of said lug.

10. In a device of the character described, the combination with an attaching-lug having its opposite sides flat and parallel, of a U-shaped member comprising two parts hinged together and adapted to embrace the flat sides of said lug at their ends, a pivot-pin extending through said lug and projecting from each side of the same, one of the parts of the U-shaped member being pivoted on said pin 120 and the other part having a perforation in its free end, and interlocking means for normally holding the latter part of said member against the lug, with the pivot-pin passing through said perforation.

11. In a device of the character described, the combination with an attaching-lug having its opposite sides flat and parallel, of a pin passing through said lug and projecting from each side of the same, a saddle or hook shaped member pivoted on one end of said pin, and a cover hinged to said saddle member and perforated to receive the other end of said pin, said cover and lug being provided

with means arranged to interlock when the parts are in normal relative position.

In testimony whereof I have hereunto subscribed my name this 22d day of March, 1905.

EDWARD B. MERRIMAN.
